UNITED STATES PATENT OFFICE.

CLEMENT L. FLYNN, OF BELLINGHAM, WASHINGTON, ASSIGNOR TO WELLES THOMPSON COMPANY, OF MINNEAPOLIS, MINNESOTA, A CORPORATION OF MINNESOTA.

SILO.

1,130,894.

Specification of Letters Patent.

Patented Mar. 9, 1915.

Application filed February 21, 1914. Serial No. 820,095.

To all whom it may concern:

Be it known that I, CLEMENT L. FLYNN, a citizen of the United States, residing at Bellingham, in the county of Whatcom and 5 State of Washington, have invented certain new and useful Improvements in Silos, of which the following is a specification.

My invention has for its object to provide an improved silo, and to such ends, 10 generally stated, the invention consists of the novel construction and combination of devices hereinafter described and defined in the claims.

The silo embodied in the several features 15 of my invention is illustrated in the accompanying drawings wherein like characters indicate like parts throughout the several views.

Referring to the drawings: Figure 1 is a 20 front elevation showing a portion of the improved silo but with the outer panel-boards removed; Fig. 2 is a vertical section taken on the line $x^2 x^2$ on Fig. 1, showing the outer panel-boards in position; Fig. 3 is a horizontal section taken on the line $x^3 x^3$ on Fig. 1 and then the outer panels; Fig. 4 is 25 a fragmentary perspective of one of the posts or uprights; Fig. 5 is a perspective view of the preferred form of panel-board; 30 and Fig. 6 is a complete horizontal section of the silo.

Referring to the drawings, 10 represents a foundation of concrete or other suitable material and is provided with a ledge or 35 sill 11 upon which the silo-wall is supported. This wall is of a polygonal form in horizontal section and is provided with a frame comprised of upright members or posts 12 which are positioned at the respective angles 40 of the wall, and horizontally disposed tie-members or rods 18 which connect the adjacent posts with each other.

The posts or upright are constructed, each 45 of a piece of timber having in each of its sides 13 and adjacent to its inner face 14, a recess 15 formed to the arc of a circle and extending the entire length of the post. Said recesses serve to house the ends 16 of horizontally disposed panel-boards 17, said 50 ends being formed to the same curvature as that of the recesses whereby close fits may be had between the posts and the panel-boards when the latter are arranged in various angular relations with respect to the 55 posts, as indicated, for example, by the full-

line positions, or by broken lines A in Fig. 3, as may be required for different diameters of silos. These boards may be made of uniform widths or of what is conventionally known as "random widths" and are formed 60 with matching top and bottom edges 17' and 17² which, by preference, are respectively of convex and concave forms, as shown in Fig. 5.

The adjacent posts of the wall, as above 65 mentioned, are connected by coupling rods or bolts 18 which extend through holes 18¹ provided in the respective posts and are secured thereto against lateral displacement by means of nuts 19 and 20 engaging screw- 70 threads provided on the bolt-ends and in juxtaposition with washers 19¹ and 20¹ which, in turn, bear against the opposite sides of the posts. Said bolts are disposed in series or groups which are designed to 75 extend entirely around the wall.

Adjacent their outer faces, the posts 13 are provided with rabbets 21 to receive the ends of horizontally arranged boards 22 having tongue-and-groove connections with 80 each other.

It is highly important to note, that in this improved silo, the rods or bolts 18, with their double sets of nuts 19 and 20, applied as shown and described, not only serve to 85 hold the uprights 14 against separating movements in respect to each other, but also against approaching movements, in respect to each other. Otherwise stated, the double-nutted rods are, in fact, combined coupling and spacing rods which coöperate with the uprights 14 to make a self-sustaining skeleton for an approximately circular silo, wherein all pairs of adjacent uprights are 90 coupled together and spaced apart from each other to any desired predetermined distance, independently of all other pairs of uprights in the entire series; and at the same time, these combined coupling and spacing rods, taken collectively, serve to tie or couple together all the uprights of the entire series, and to space the same apart from each other approximately on the chords of 95 arcs of a common circle.

The uprights are grooved, as described, on 100 their vertical faces, thereby adapting the pairs of adjacent uprights to receive and seat the straight panel-boards 17 with freedom for a limited variation in the angular 105 relation of the boards to the uprights; and 110

when the panel-boards are thus in position, the elements above named complete a silo which is approximately of circular form. As a matter of fact, the posts are located at the ends of chords of arcs, preferably of equal arcs of a circle described from a common center. The fact that the above described skeleton is self-sustaining, and that every pair of adjacent uprights are independent of every other pair, in respect to their relative positions, when the coupling and spacing rods are applied thereto, is of large importance for simplicity of construction, shipment, and facility of erection.

Any pair of uprights can be placed in proper working position and tied or coupled together and spaced apart to the desired predetermined distance, before the erection of any additional uprights, if so desired, and the panel-boards can be applied between the single pair of uprights, then additional uprights may be added and additional coupling and spacing rods be applied and panel-boards placed between the next adjacent pair, until the silo is completed; or additional pairs of uprights can be placed anywhere else around the common center, as by different workmen, and the panel-boards be applied between the same, thus enabling several sets of workmen to carry on the erection, simultaneously, from different points. These are matters of large importance in the building of silos. The said self-sustaining skeleton and the panel-boards 17, of course, constitute the silo proper, and after this is completed, the boards 22 are applied to their rabbeted seats 21 in the outwardly project-

ing portions of the posts 12, and secured thereto by screws or nails 26, thus affording an outer wall to the main silo with an air jacket space between the two.

What I claim is:

1. A self-sustaining skeleton for an approximately circular silo, which skeleton comprises a series of uprights and a series of horizontally disposed combined-coupling and spacing rods serving to couple or tie together and to space apart all pairs of adjacent uprights independently of any other pair of the entire series of uprights, and also to couple together and space apart all the uprights of the entire series approximately on the chords of arcs of a common circle, substantially as described.

2. An approximately circular silo comprising a series of uprights grooved on their vertical faces to receive horizontal panel-boards, a series of horizontally disposed combined-coupling and spacing rods serving to couple together and space apart all pairs of adjacent uprights independently of any other pair of the entire series of uprights, and to couple together and space apart all the uprights of the entire series, approximately on the chords of arcs of a common circle, and horizontal panel-boards seated in the grooves of adjacent pairs of said uprights, substantially as described.

Signed at Bellingham, Wash., this 14th day of February, 1914.

CLEMENT L. FLYNN.
